CARL A. EVANS, OF ROSE TOWNSHIP, RAMSEY COUNTY, MINNESOTA, ASSIGNOR TO THE PHOTOPLATING COMPANY, OF MINNEAPOLIS, MINNESOTA, A CORPORATION OF SOUTH DAKOTA.

DISPLAY PLATE.

Application filed June 4, 1925. Serial No. 34,886.

This invention relates to improvements in display plates, designed particularly for advertising purposes, and adapted to be secured to the inner surface of a sheet of 5 glass, in a window or door, or constituting a part of a wall of a show case or other structure.

The invention consists generally in a display plate having its display surface provided with a protruding strip or band of fibrous material permeated with a soluble cement which will become softened upon the application thereto of a suitable solvent and, when the plate is pressed against the 15 surface of the glass, will permanently adhere thereto, thereby rigidly and firmly securing the plate to the glass in position so that the display matter upon the surface of the plate that is next to the glass can be 20 seen through the glass.

The invention consists further in the constructions and combinations hereinafter described and particularly pointed out in the claims.

25 In the accompanying drawings forming part of this specification,

Figure 1 is a front elevation of the display plate secured to the inner surface of a sheet of glass.

30 Figure 2 is a vertical section on the line 2—2 of Figure 1;

Figure 3 is a perspective view of the inner face of the plate with the fibrous band partially removed from its retaining groove.

35 In the drawings, 2 represents a suitable plate which may be formed of metal, glass, paper or a composition of any other suitable material.

I have here indicated a circular metallic 40 plate dished in form. The inner surface of this plate, that is to say, the surface that is intended to be next to the glass to which the plate is affixed, is provided with any suitable design, such as an advertisement or 45 an announcement of goods for sale or exhibition, or any matter that it is designed to display to the public. As here shown, the plate is provided near its edge with a groove or recess 3, which, as shown, extends around 50 the plate near the edge thereof, and is substantially of semi-circular form in cross section. Within this groove is placed a strip or band 4 of suitable fibrous material that

is saturated with a soluble cement by means of which the surface of the strip that is in 55 contact with the walls of the groove is rigidly and permanently cemented thereto. The strip projects or protrudes beyond the surface of the plate and forms a ridge thereon. I have here shown a strip that is cylindrical in cross section and that projects for 60 about one-half of its diameter outside of the groove 3 in the plate.

The portion of the strip that protrudes from the groove will, when the cement with 65 which it is saturated becomes hard, be of sufficient rigidity so that the plate may be handled for sale or shipment as though the strip were merely a protruding rib on the plate. When the user desires to attach the 70 plate to a surface such as a window, door or the walls of a showcase, or other structure, a suitable solvent is applied to the protruding portion of the strip and the cement will thereby be softened. The plate 75 may then be placed against the glass surface to which it is to be attached and being pressed firmly against such surface, the projecting surface of the saturated strip will 80 adhere firmly and completely to the glass 85 surface as indicated in Figure 2 of the drawings. The display plate will thereby be rigidly and firmly secured to the glass surface and the matter on the inner surface of the plate will be visible through the glass.

While I have shown a circular plate with a circular groove to receive the cementing strip, it will be understood that the plate may be of any desired shape or size and the groove or recess to receive the strip may 90 be made to conform to the outline or shape of the plate. While I have shown a continuous groove or recess and a strip in the form of a continuous band therein the groove or recess and strip may be discontinuous or formed in a series of short sections, if desired.

I claim as my invention:

1. A display plate provided with a recess surrounding its display surface with a 100 fibrous strip secured in said recess and projecting beyond the face of the plate, the projecting portion of the strip being saturated with a soluble cement, for the purpose set forth.

2. A display plate provided with a recess

extending continuously around the display surface of the plate and near the edge thereof, with a fibrous strip secured in said recess and projecting beyond the surface of the plate, the projecting portion of said strip being saturated with a soluble cement, for the purpose set forth.

3. A display plate provided with a comparatively narrow recess encircling its dis-

play surface, a fibrous strip fitting within said recess and projecting outwardly beyond the surface of the plate, the projecting portion of said strip being saturated with a soluble cement for the purpose specified.

In witness whereof, I have hereunto set my hand this 2nd day of June, 1925.

CARL A. EVANS.
